(57) **CLAIM**

The ornamental design for a can dispenser as shown and described.

DESCRIPTION

FIG. 1 is a top perspective view of a can dispenser showing our new design;

FIG. 2 is bottom perspective view thereof;

FIG. 3 is a front view of thereof;

FIG. 4 is a rear view of thereof;

FIG. 5 is a left view of thereof;

FIG. 6 is a right view of thereof;

FIG. 7 is a top view of thereof;

FIG. 8 is a bottom view of thereof; and,

FIG. 9 is an enlarged view of a portion labeled as "9" on FIG. 1.

The dash-dash broken lines in the drawings illustrate portions of the can dispenser that form no part of the claimed design. The dot-dash broken lines in the drawings illustrate the boundaries of the portions shown enlarged in the drawings and form no part of the claimed design.

1 Claim, 9 Drawing Sheets
